F. B. COOK.
ELECTRICAL PROTECTIVE DEVICE.
APPLICATION FILED MAY 10, 1911.

1,086,028.

Patented Feb. 3, 1914.

UNITED STATES PATENT OFFICE.

FRANK B. COOK, OF CHICAGO, ILLINOIS.

ELECTRICAL PROTECTIVE DEVICE.

1,086,028.

Specification of Letters Patent.

Patented Feb. 3, 1914.

Application filed May 10, 1911. Serial No. 626,386.

To all whom it may concern:

Be it known that I, FRANK B. COOK, a citizen of the United States, residing at Chicago, in the county of Cook and State of Illinois, have invented certain new and useful Improvements in Electrical Protective Devices, of which the following is a specification.

This invention relates to electrical protective devices and refers more particularly to a protector unit of the class disclosed in my prior Patent No. 990,229, issued April 25, 1911, such protector units being adapted to be used upon cable terminals and in similar situations.

The object of the present invention is to provide improved means for mounting the fuse-holding spring members upon the base-plate of the unit.

20 In the accompanying drawings, Figure 1 is a plan view, with parts in section, of a protector unit embodying the features of my invention. Fig. 2 is a side elevation thereof, the fuses being removed. Fig. 3 is a longitudinal section on line 3—3 of Fig. 2. Fig. 4 is a fragmentary under side view of the fuse supporting clips and attaching block at one end of the device.

The present embodiment of my invention 30 comprises a base-plate 4 which is adapted to be secured to a suitable supporting plate A, the latter preferably taking the form shown in Fig. 1 so that it may be used as one side of a cable terminal in a well known manner. The means for attaching the base-plate 4 to the plate A may be substantially the same as that shown in my said patent, 35 said means comprising hooks *a* on the plate A arranged to overlie one end portion of the base-plate, and hollow binding posts *b* forming a permanent part of the cable terminal plate A, said binding posts being adapted to be gripped by spring fingers upon the protector unit. Insulating sleeves 45 *c* serve to insulate the binding posts *b* from adjacent parts. The plate A is adapted to support a plurality of the protector units in this invention. The base-plate 4 may have stiffening flanges 5 at its side edges.

50 At each end of the base-plate 4 is a pair of spring members 6 7, said members supporting between them a pair of inclosed fuses 8. Between each of the members 6 and the plate 5 is frictionally held a suitable light-

ning arrester 9. The inner end of each of 55 the members 6 has a pair of spring fingers 6^a arranged to grip one of the binding posts *b*. The base-plate 4 has openings 4^a therein to receive the binding posts *b*.

The means for securing the pair of spring 60 members 6 to the base-plate comprises a block 10 of insulating material such as hard rubber, the members 6 being securely fixed thereto in any suitable way, preferably that disclosed in my aforesaid patent. Within 65 the block 10 is embedded a nut 11. A screw 12 passing upwardly through an opening in the base-plate 4 is adapted to engage the embedded nut 11 to secure the block 10 firmly to the base-plate. Preferably the 70 base-plate has one or more tangs 13 punched upwardly therefrom, said tangs being arranged to lie in recesses 14 formed in the bottom of the block 10 for the purpose of preventing rotation or twisting movement 75 of said block with reference to the base-plate 4. The metal of the base-plate at the edge of the opening for the screw 12 may be turned up as shown in Fig. 3, if desired, so that the head of said screw will lie flush 80 with the face of the base-plate. Preferably a sheet 15 of mica or other similar material is interposed between the block 10 and the base-plate 4. The pair of spring members 7 at the opposite end of the base-plate 4 are 85 secured to a sleeve 16 of insulating material, preferably in the manner hereinbefore referred to, said sleeve having its inner end reduced in diameter to form a shoulder 17, 90 said reduced end passing through an opening in the base-plate 4 and having a nut 18 threaded upon its inner end, said nut bearing against the base-plate 4 at the side opposite to the shoulder 17 and serving to firmly secure the sleeve 16 to said base-plate. 95 Tangs 19 punched upwardly from the base-plate and lying in recesses formed in the shoulder 17 serve to prevent rotation or twisting movement of the sleeve 16 with reference to the base-plate 4.

100 20 is a sheet of mica or similar material interposed between the shoulder 17 and the adjacent face of the base-plate. If desired the spring member 7 may have short sleeves 21 fixed thereto, said sleeves being internally 105 threaded to receive binding screws 22 to facilitate the attachment of electric wires *d* which may be inserted through the insulat-

ing sleeve 16 from the inside of the cable terminal. Another wire *e* may be suitably attached to the binding post *b*.

I claim as my invention:

- 5 1. In a device of the character described, the combination of a base-plate, a fuse-supporting device, and means for securing said device to said base-plate comprising an insulating member to which said device is 40 fixed, a metallic nut embedded in said member, a screw passing through an opening in said base-plate and engaging said nut, and means for preventing rotation of said insulating member with reference to said base- 45 plate.
- 10 2. In a device of the character described, the combination of a base-plate, a fuse-supporting device and means for securing said device to said base-plate comprising an insulating member to which said device is secured, a metallic nut embedded in said member, a screw passing through an opening in said base-plate and engaging said nut, and means on said base-plate engaging said 50 insulating member to prevent rotation thereof.
- 15 3. In a device of the character described, the combination of a base-plate, a fuse-supporting device, and means for securing said device to said base-plate comprising an insulating member to which said device is fixed, means for attaching said insulating member to said base-plate, and means for 55 preventing rotation of said member with reference to said base-plate.
- 20 4. In a device of the character described, the combination of a base-plate, a fuse-supporting device, an insulating member to 60 which said device is fixed, a nut embedded in said member, a screw passing through an opening in said base-plate and engaging said nut, said member having a recess in 65 one face, and tangs struck up from said base-plate and lying in said recess.

which said device is fixed, means for attaching said member to said base-plate, and tangs struck up from said base-plate and engaging said insulating member for preventing rotation of the latter.

5. In a device of the character described, the combination of a base-plate, a fuse-supporting device, an insulating member to which said device is fixed, a nut embedded in said member, a screw passing through an opening in said base-plate and engaging said nut, said member having a recess in 50 one face, and tangs struck up from said base-plate and lying in said recess.

6. A device of the character described comprising a base plate, a fuse-supporting device, an insulating member upon which 55 said fuse supporting device is mounted, a nut fixedly embedded in said insulating member at the side adjacent to said base plate, said nut being insulated from said fuse-supporting device by said insulating 60 member, the latter having a recess surrounding said nut, said base plate having an opening registering with said nut and having the material surrounding said opening bent laterally to lie in said recess in the insulating 65 member, said laterally bent portion forming a countersink in the base plate, and a screw passing through said opening and threaded in said nut, the head of said screw lying in said countersink flush with the base plate. 70

In testimony whereof I hereby affix my signature in the presence of two witnesses.

FRANK B. COOK.
